UNITED STATES PATENT OFFICE.

NELS PAULSON, OF EVANSTON, ILLINOIS.

DESIGN FOR A TOY DOG.

Application filed March 27, 1929. Serial No. 30,637. Term of patent 14 years.

To all whom it may concern:

Be it known that I, NELS PAULSON, a citizen of the Kingdom of Sweden, residing at Evanston, in the county of Cook and State of Illinois, have invented a new, original, and ornamental Design for a Toy Dog, of which the following is a specification, reference being had to the accompanying drawings, forming part thereof:

The figure is a perspective view of a toy dog, showing my new design.

I claim:

The ornamental design for a toy dog, as shown.

NELS PAULSON.
